US0D1081263S

(12) **United States Design Patent** (10) Patent No.: **US D1,081,263 S**
Bodner (45) Date of Patent: ** Jul. 1, 2025

(54) **WATER BOTTLE**

(71) Applicant: **Razor Group Acquisition II GmbH**,
 Berlin (DE)

(72) Inventor: **Samuel Bodner**, Berlin (DE)

(**) Term: **15 Years**

(21) Appl. No.: **35/521,805**

(22) Filed: **Jul. 1, 2024**

(80) **Hague Agreement Data**

Int. Filing Date: **Jul. 1, 2024**

Int. Reg. No.: **DM/238761**

Int. Reg. Date: **Jul. 1, 2024**

Int. Reg. Pub. Date: **Aug. 2, 2024**

(51) **LOC (15) Cl.** **07-01**

(52) **U.S. Cl.**

USPC **D7/510**; D7/392.1
